UNITED STATES PATENT OFFICE.

HORACE R. ALLEN, OF INDIANAPOLIS, INDIANA.

HARVESTER-CUTTER-BAR LIFTER.

SPECIFICATION forming part of Letters Patent No. 268,375, dated December 5, 1882.

Application filed February 7, 1882. (No model.)

To all whom it may concern:

Be it known that I, HORACE R. ALLEN, of the city of Indianapolis, county of Marion, and State of Indiana, have invented certain new and useful Improvements in Cutter-Bar Lifters, of which the following is a specification.

The object of my said invention is to raise the cutter-bars of mowing or such like machines by power from the machine itself instead of by the common hand-lever, as has been usual.

This object is accomplished by and the invention consists in mounting a ratchet-wheel on the axle of the machine, or on a shaft hanging upon said axle or shaft, a stirrup carrying another shaft or rod connected with any ordinary crank mechanism for lifting the cutter-bar, and providing a device in connection with said stirrup by which when said second shaft or rod is partially rotated a connection between it and said ratchet-wheel will be formed, whereby said rod or rock-shaft will be drawn longitudinally, and thus rotate said crank mechanism attached to the cutter-bar and lift said cutter-bar.

The invention further consists of the combination, with the crank mechanism aforesaid, and the end of the rod or rock-shaft attached thereto, of a non-rotating disk or some equivalent device on the shaft of said crank mechanism or some other rigid part of the machine near it, on one side of which, at the proper point, is a projection in the form of an inclined plane which engages with the bent end of said rod or rock-shaft or a projection thereon, reversing its rotation and thus forcing a disengagement between the connecting device which connects its support at the other end to the ratchet-wheel and said ratchet-wheel, and also thereby locks the crank mechanism and holds the cutter-bar in position.

The invention still further consists in some details of construction, all as will be hereinafter more particularly set forth.

Referring to the accompanying drawings, which are made a part hereof, and on which similar letters of reference indicate similar parts, Figure 1 is a top or plan view of a mowing-machine to which my said invention has been applied; Fig. 2, a longitudinal vertical section thereof on the dotted line *z z*, the in-

vention proper being shown in side elevation; Fig. 3, a side elevation of the mechanism relating particularly to this invention, the surrounding parts being removed; Fig. 4, a top plan of the same; Fig. 5, a detail vertical section on the dotted line *y y*; Fig. 6, a similar view on the dotted line *x x*; Fig. 7, a horizontal section of the stirrup, looking downwardly from the dotted line *w w*; and Fig. 8, a section of the mechanism at the front end, looking to the right from the dotted line *v v* in Fig. 3.

In said drawings, the portions marked A represent the wheels of the mowing-machine; B, the axle thereto; C, the casing or framework of the machine; D, the seat; E, the tongue; F, a ratchet-wheel mounted on the axle B or on an equivalent shaft; G, a stirrup hung on said axle or shaft, preferably having a bearing on each side of said ratchet-wheel; H, a rock-shaft or rod mounted at one end in the lower end of said stirrup and connected at the other with a crank mechanism for lifting the cutter-bar; I, a slide whereby a connection may be made between said ratchet-wheel and said rod; J, a crank-wheel to an arm on which said bar is connected; K, a chain or rod connecting another arm on said wheel to the cutter-bar; L, said cutter-bar; M, the shaft on which the wheel J is mounted, and N a non-rotating disk on the same shaft as the crank-wheel.

The wheels A, axle B, casing C, seat D, and tongue E are or may be of any usual or approved form or construction in machines of this character, and need no special description.

The ratchet-wheel F may be of the ordinary form, but I prefer that it shall have round-faced corrugations instead of the ordinary angular teeth as engaging devices, so that the device I, which should be provided with similar corrugations, may slip past said wheel when forced against it with only a light pressure, and thus form a brake for use while lowering the cutter-bar, as will be hereinafter explained.

The stirrup G is mounted on the shaft B, as shown, being preferably bifurcated, so that it may have a bearing on both sides of the ratchet-wheel. It hangs loosely on the shaft, in perpendicular position, except when forced around by the operation of the mechanism, as

hereinafter described. It contains a rocking bearing, h^3 , for the rod or rock-shaft H at its lower end, and slides or ways on its inner sides for the sliding device I.

5 The rod or rock-shaft H has bearing in and is attached to both the stirrup G and the crank-arm j^2 on the crank-wheel J . At the end mounted in the stirrup G this rod is provided with a crank, h , which rests against the 10 slide I, or to which said slide is attached, and at the other end with a bend or projection, h' , which engages with the disk N . Centrally on 15 on said rod or rock-shaft is an arm, h^2 , and attached to said arm is a treadle, H^2 , by means of which a partial rotation may be given to said rod.

The slide I rests in grooves or ways in the inside faces of the sides of the stirrup G , and is operated to move up and engage with the 20 ratchet-wheel F by the crank in the rod or rock-shaft H , when the latter is rotated by means of the treadle H^2 and arm h^2 , whereby the stirrup becomes rigid with said wheel and moves therewith until the engagement between 25 said slide and said wheel is released, which is either done by the gravity of the parts when the pressure upon the treadle H^2 is removed or by the action of the inclined plane upon the disk N , as will hereinafter be 30 described. A slight pressure upon the treadle H^2 , when the cutter-bar is being lowered, causes this slide to bear lightly against the wheel F , and thus act as a brake and prevent the cutter-bar from descending too rapidly.

35 The crank-wheel J is a wheel or hub loosely mounted on a shaft, M , and having two arms or projections, to one of which, j' , the chain or rod K is attached, and through the other of which, j^2 , the rod H passes. When this wheel 40 is rotated in the reverse direction to the rotation of the axle, which is done in this case by means of the said rod H , the cutter-bar is of course lifted by means of the chain K .

The chain K and cutter-bar L and shaft M 45 are not dissimilar to other devices of like character.

The disk N is rigidly mounted upon the shaft M , and, as said shaft is non-rotating, occupies an unvarying position. It is provided at the 50 proper point with an angular projection, n , which, as the rod or rock-shaft H is moved endwise by the action of the ratchet-wheel, as hereinbefore described, will, when the bend or projection h' on said rod comes in contact therewith, raise the same, thus reversing the rotation of said rod from that given it by the action of the treadle H^2 , throwing down the crank from lifting contact with the slide I, thus disengaging said slide from the ratchet-wheel F 55 and stopping the endwise movement of the rod or rock-shaft H . The projection n is somewhat larger than is necessary to accomplish the above-specified object, and therefore after the bend or projection h' in the rod H has 60 passed over it said bend or projection is enabled to drop back a part of the way and catch

on the back of said projection n , which prevents said rod and the crank-wheel J from moving back, and thereby letting the cutter-bar down, until the part h' is released from its 70 said engagement with said projection n . In order to prevent said part h' from falling down too far, a second projection, n' , of somewhat less height than the projection n , is formed on the disk immediately in the rear of said projection n . Instead of this disk N , any device rigidly attached to the shaft M or to any adjacent part of the machine, and provided with the inclined projection n , might be used, and would be considered by me a substantial equivalent for said disk, as the latter has no function in this machine apart from what is performed by said projection. When it is desired to drop the cutter-bar the projection or bent portion h' at the end of the shaft H is raised 80 out of engagement with the projection n , which may be done by the operator inserting his toe in the loop h^4 and lifting thereon.

The operation of my said invention may be recapitulated as follows: When it is desired to 90 raise the cutter-bar the operator presses upon the foot-lever H^2 , thereby, through the arm h^2 , partly rotating the rod or rock-shaft H , which, through the crank h , raises the slide I, forcing it into engagement with the ratchet-wheel F , 95 which is firmly fixed on the axle B , and therefore, when the machine is in motion, is continuously in rotation. The slide I, being firmly held in grooves in the stirrup G , (which is hung loosely on the axle,) then causes said stirrup to 100 move with said wheel F and pull the rod or rock-shaft H , which is attached to said stirrup, and through said rod partially revolve the crank-wheel J , which, through the arm j' and chain K , lifts the cutter-bar. When the cutter-bar has reached the proper height the projection n is so arranged that it comes in contact with the bent portion h' of the shaft, rotating the rock-shaft in the reverse direction from that in which it was rotated by the foot-lever H^2 , 110 thus throwing down the crank h and permitting the slide I to become disengaged from the wheel F , thus stopping the movement. The bent portion h' engages behind the projection n , and is held thereby until released, thus preventing the crank-wheel from receding from its 115 position. This holds the cutter-bar from falling.

Having thus fully described my said invention, what I claim as new, and desire to secure 120 by Letters Patent, is—

1. In a cutter-bar lifter for mowing and like machines, the combination of a ratchet-wheel on the shaft or axle, a stirrup depending from said shaft or axle, a rock-shaft, H , connected at 125 one end to said stirrup and at the other to a crank-wheel mechanism for lifting the cutter-bar, a slide in said stirrup, means which operate to engage the same with the ratchet-wheel, said crank-wheel mechanism, a connection 130 from the same to the cutter-bar, and said cutter-bar, substantially as set forth.

2. In a cutter-bar lifter for mowing and like machines, the combination of the rock-shaft H, having crank portion h, with the stirrup G, slide I, and ratchet-wheel F, whereby when said shaft is rocked said slide will be brought into engagement with said wheel, and thus cause said stirrup to move therewith, substantially as set forth.
3. In a cutter-bar lifter for mowing and like machines, the combination, with the rock-shaft H, having bent end h' and crank-wheel mechanism, of the disk N, having a projection, n, whereby said shaft is first partly rotated and it and said crank-wheel mechanism then fastened, substantially as set forth.
4. The combination of the axle or shaft B, ratchet-wheel F, stirrup G, slide I, shaft H, crank-wheel J, having suitable arms or projections, chain or rod K, and the cutter-bar, substantially as set forth.
5. The combination, in a mowing or like machine, of the cutter-bar, the immediate means for lifting the same, the main shaft or axle, the ratchet-wheel F, mounted thereon, the stirrup G, depending therefrom, the slide I, operating in ways in said stirrup, and means which are adapted to engage said slide with said ratchet-wheel and at the same time connect the mechanism of which said slide forms a part with the said immediate means for raising the cutter-bar, substantially as set forth.

In witness whereof I have hereunto set my hand and seal, at Indianapolis, Indiana, this 3d day of February, A. D. 1882.
